UNITED STATES PATENT OFFICE.

FRED H. ARNOLD, OF NEW BRITAIN, CONNECTICUT, ASSIGNOR TO THE LANDERS, FRARY & CLARK, OF SAME PLACE.

DESIGN FOR A CUTLERY-HANDLE.

SPECIFICATION forming part of Design No. 22,563, dated June 27, 1893.

Application filed May 31, 1893. Serial No. 476,149. Term of patent 7 years.

To all whom it may concern:

Be it known that I, FRED H. ARNOLD, a citizen of the United States, residing at New Britain, in the county of Hartford and State of Connecticut, have invented and produced a new and original Design for Cutlery-Handles, of which the following is a specification, reference being had to the accompanying drawings, in which—

10 Figure 1 is a side elevation of a cutlery handle showing my design, and Fig. 2 is an edge view of the same.

The contour of my handle in side view is clearly shown in Fig. 2. The ferrule portion 15 A is ornamented by a wavy band 1, extending obliquely across the handle, a cluster of

leaflets 2, and a scroll shaped horn 3 bordered by a row of leaflets. On each side of the body portion B of the handle there are two ornaments 4 and 5, leaving a plain portion 6 at the upper edge or back of the handle and another plain portion 7 at the butt, while the greater portion of the remaining surface is fluted as shown. 20

What I claim is—

25 The design for cutlery handles substantially as herein shown and described.

FRED H. ARNOLD.
